CLAIM

The ornamental design for a bistro table heater, as shown and described.

DESCRIPTION

FIG. 1 is a perspective view of the bistro table heater showing the design;

FIG. 2 is a front view thereof;

FIG. 3 is a left side view thereof;

FIG. 4 is a right side view thereof;

FIG. 5 is a rear view thereof; and,

FIG. 6 is a top view thereof.

The bottom view is not shown, as it forms no part of the claimed design.

1 Claim, 6 Drawing Sheets

FIG. 1

FIG. 2

FIG. 3

FIG. 4

FIG. 5

FIG. 6
